UNITED STATES PATENT OFFICE

2,107,271

ZIGZAG STITCH-FORMING MECHANISM
FOR SEWING MACHINES

Edward B. Allen, deceased, late of Newtown, Conn., by Josephine W. Allen, administratrix, Newtown, Conn., and Maurice D. Knox, Devon, and Harold C. Faulkner, Long Hill, Conn., assignors to The Singer Manufacturing Company, Elizabeth, N. J., a corporation of New Jersey

Original application November 10, 1936, Serial No. 110,026. Divided and this application March 18, 1937, Serial No. 131,618

5 Claims. (Cl. 112—159)

This invention relates to sewing machines and has for an object to provide an improved and simplified zigzag stitch-forming mechanism, including loop-taker-compensating mechanism, which, although of general utility in the zigzag lock-stitch sewing machine art, is adapted more particularly for use in a lock-stitch buttonhole sewing machine such as disclosed in our copending application, Serial No. 110,026, filed Nov. 10, 1936, of which this application is a division.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings Fig. 1 is a right side elevation of a buttonhole sewing machine embodying the invention. Fig. 2 is a vertical section taken longitudinally of the machine bed through the shuttle mechanism mounted therein. Fig. 3 is an elevation of the parts shown in Fig. 2 looking from the right. Fig. 4 is a vertical section through the shuttle-carrying turret looking at the face of the shuttle. Fig. 5 is a section on the line 5—5, Fig. 2. Fig. 6 is a section on the line 6—6, Fig. 4. Fig. 7 is a section on the line 7—7, Fig. 4. Fig. 8 is a detail view of the pin and star-wheel drive through which the needle-vibrating mechanism is actuated. Fig. 9 is a side elevation of the needle-vibrating mechanism. Fig. 10 is a section on the line 10—10, Fig. 9.

Fig. 11 is a vertical section on the line 11—11, Fig. 9. Fig. 12 is a section on the line 12—12, Fig. 11. Fig. 13 is an elevation of the lower end of the needle-bar showing the yoke and needle-clamp-block. Fig. 14 is a perspective view of the rotary needle-bar bushing, and Fig. 15 is a perspective view of the laterally reciprocatory guide-block for the needle-clamp-block.

The machine frame comprises the hollow box-like bed 1 from one end of which rises the standard 2 of the overhanging bracket-arm 3 terminating in the head 4.

Journalized within and lengthwise of the bed 1, is the main sewing shaft 5, Fig. 1, which, through the one-to-one bevel gears 6, 7, drives the vertical shaft 8 journalized within the standard 2. The shaft 8 has a one-to-two speed-multiplying bevel-gear driving connection 9 with the upper or needle-bar-reciprocating shaft 10

which is journalized within and lengthwise of the bracket-arm 3 and has the usual crank 11 and link-connection 12 with the vertically reciprocatory hollow needle-bar 13 mounted in the head 4.

The hollow needle-bar 13, Figs. 12 and 13, has fixed to its lower end the yoke 14 carrying the cross-pin 15 on which is slidably mounted the needle-clamp-block 16 having at its upper end a guideway 17, Fig. 11, embracing the horizontal member of the yoke 14. The block 16 carries the eye-pointed needle 18. The yoke 14 is slidably received at one end in the guideway 19, Figs. 12 and 14, in a vertical arm 20 depending from a block 21 fixed to the lower end of the needle-bar-bearing bushing 22 journalized in the head 4 and having the pinion 23 fixed to its upper end, whereby turning movements may be imparted to it, as in stitching around the eyelet-end of a buttonhole.

The block 21 also has depending from it another arm 24 which is spaced from the arm 20. The arms 24 and 20 carry a cross-pin 25 on which is horizontally slidably mounted a vertical guide-arm 26 having a guideway 27 receiving the spaced rearward extension 28 of the needle-clamp-block 16. The guide-block 26 is steadied on the cross-pin 25 by having its upwardly extending end 29 slidably received in a guideway 30, Fig. 11, in the block 21; said guideway being completed by the cover-plate 31. The needle 18 is thus supported for endwise reciprocatory and laterally vibratory movements in a rotary support which is turnable about a vertical axis.

The vertical guide-block 26, which imparts the lateral vibratory movements to the needle-clamp-block 16, is connected by a link 32, Fig. 9, of adjustable length to an arm 33 fixed to one end of a rock-shaft 34 journalized in the block 21 and having fixed to its other end an arm 35, Fig. 10, which pivotally carries a guide-block 36 received in the circular groove 37 in the ring member 38 fixed to the lower end of the vertical slide-rod 39, Fig. 1, journalized in the head 4. The ring 38 is steadied by the fixed guide-pin 40 which it slidably engages. Thus, vertical movements of the slide-rod 39 and ring 38, impart lateral vibratory movements to the needle 18 in any position of the plane of vibration of the latter.

The rod 39 is reciprocated vertically, to impart lateral vibratory movements to the needle 18, by the following mechanism. Fixed to the rod 39 is a block 41, Fig. 1, which extends laterally through a slot 42 in one side wall of the head 4 and has pivotally connected thereto one end of

a link 43 the other end of which is adjustably and pivotally secured in the slotted segmental arm 44 of a bell-crank lever 44, 45 fulcrumed at 46 on the head 4. The arm 45 of the bell-crank lever is connected by the link 47 to the adjustable crank-pin 48 projecting from the outer face of a crank-head 49 pivoted at 50, Fig. 1, on the disk-shaped head 51, at one end of the shaft 52 journaled within and transversely of the bracket-arm standard 2. Movement of the crank-head 49 about the pivot-screw 50 changes the eccentricity or operative radius of the crank 48 relative to the axis of its drive-shaft 52.

This adjustable crank mechanism is built substantially in accordance with the disclosure in the Allen et al. application, Serial No. 759,200, filed Dec. 26, 1934, and need not be specifically described herein. It will suffice to explain that the shaft 52 carries a bevel pinion 53 which is driven by the bevel gear 54 fixed to the vertical shaft 55, Figs. 1 and 8, carrying at its lower end a pinion 56 driven by a gear 57 fixed to the vertical stub-shaft 58 to which is also fixed the star-wheel 59 driven by the diametrically opposed pins 60 at the lower end of the vertical shaft 8. The pin and star-wheel drive imparts intermittent rotary motion to the shaft 55, which, in turn, imparts intermittent semi-rotational impulses to the crank 48 which actuates the needle-vibrating mechanism above described.

Detachably mounted on the transverse frame-member 61, within the bed 1, is the turret carrier block 62 having the upper and lower spaced bearings 63, 64 for the tubular stem 65 of the turret 35 66 carrying the yieldingly separable shuttle race rings 67, 68, Fig. 6, in which is journaled the conventional sewing machine shuttle 69 carrying the usual bobbin 70, Fig. 2, of under thread. The shuttle 69 is oscillated in its raceway by means of a shuttle driver 71 of usual form which is carried by the shaft 72 journaled in the bearing 73 at the rear of the turret 66. The shaft 72 has pinned to it a pinion 74 meshing with the sector gear 75 fixed to one of the trunnions 76, Fig. 7, of the rocking sleeve 77 journaled in the turret 66. The sleeve 77 is entered by the pin 78 the bifurcated head 79 of which is pivoted at 80 to the upper end of the reciprocating rod 81 slideable in the turret stem 65.

Screwed to the longitudinally ribbed face 82, of the rod 81 are two spaced gibs 83 which extend outwardly through the slot 84 in the tubular stem 65 of the turret and embrace the ring member 85 which surrounds the stem 65. The ring member 85 is carried by the slide-plate 86 guided in the vertical guide-way 87 in the turret-carrier block 62. The slide-plate 86 has a stud-pin 88 projecting rearwardly therefrom and this stud-pin is connected by the pitman 89 to the crank 90 on the shaft 91 journaled in the carrier 92 which, in turn, is journaled on the bearing bushing 93 in which the main sewing shaft 5 is journaled. The bushing 93 is set into an aperture 94 in the frame member 61. The shaft 91 has fixed to it a pinion 95 driven by the gear 96 of double its size on the main shaft 5.

In order to compensate the shuttle mechanism for the different lateral positions of the laterally vibratory needle, provision is made to accelerate 70 and retard the shuttle-driving shaft 91 so that the shuttle beak will be properly timed relative to the needle in the different lateral positions of the needle. To this end there is mounted on the main sewing shaft 5 an eccentric 97 embraced by 75 the eccentric-follower lever 98 the forked lower

end of which slidably embraces the anchor-block 99 fixed to the rockable pin 100 journaled in the frame block 101 secured to the frame cross-member 61. The upper forked end of the lever 98 embraces the block 102 rotatively free on the shaft 91 and confined between the collar 103, Fig. 2, and the head of the screw 104. Thus, rotation of the main shaft 5 imparts oscillatory movement to the carrier 92 for the crank-shaft 91 which latter is given two rotations for one complete to-and-fro oscillation of the carrier 92.

The shuttle thread is delivered through the apertured end of the thread-case arm 105 in which the bobbin 70 is housed; the arm 105 being freely received in the notch 106 in the plate 107 15 screwed to the outer shuttle race ring 68 which is pressed by the springs 108 against the inner shuttle race ring 67. The thread-case is thus restrained from oscillating with the shuttle 69. There is mounted on the vertical back-plate of 20 the shuttle race the shank 109 of the button-like needle-throat member 110 formed with the needle-receiving slot 111. The needle-throat member supports the work against the thrusts of 25 the needle.

The turret and needle-bar rotating bushing are coaxially mounted and are turned in unison by the usual means, to position the stitches radially around one end, for example, the eyelet-end of the buttonhole; such means being disclosed, for example, in U. S. Patent No. 15,324, 30 reissued Apr. 4, 1922, and in our said copending application.

Having thus set forth the nature of the invention, what we claim herein is:—

1. In a lock-stitch sewing machine, the combination with a reciprocating and laterally vibratory needle, of a circularly moving loop-taker, a bobbin, a rotary driving shaft, a driving gear carried thereby, a driven shaft, a pinion of half the size of said driving gear mounted on said driven shaft and meshing with said driving gear, a carrier for said driven shaft mounted for oscillatory movement about the axis of said driving shaft, means on said driving shaft and connections to oscillate said carrier, and means actuated by said driven shaft for imparting circular movement to said loop-taker. 40

2. In a lock-stitch sewing machine, the combination with a reciprocating and laterally vibratory needle, of a circularly moving loop-taker, a bobbin, a rotary driving shaft, a driving gear carried thereby, a driven shaft, a pinion of half the size of said driving gear mounted on said driven shaft and meshing with said driving gear, 55 a carrier for said driven shaft mounted for oscillatory movement about the axis of said driving shaft, an eccentric on said driving shaft, a vibratory lever actuated by said eccentric and connected to impart oscillatory movement to said 60 carrier, and means actuated by said driven shaft for imparting circular movement to said loop-taker.

3. In a lock-stitch sewing machine, the combination with a reciprocating and laterally vibratory needle, of a circularly moving loop-taker, a bobbin, a rotary driving shaft, a driving gear carried thereby, a driven shaft, a pinion of half the size of said driving gear mounted on said driven shaft and meshing with said driving gear, a 70 carrier for said driven shaft mounted for oscillatory movement about the axis of said driving shaft, means on said driving shaft and connections to oscillate said carrier, a crank on said driven shaft, and a pitman actuated by said 75

crank and connected to impart circular movement to said loop-taker.

4. In a buttonhole sewing machine, a frame, a turret journaled in said frame, an oscillatory shuttle and bobbin mounted in said turret, an endwise reciprocating shuttle-actuating rod mounted in and coaxially with said turret, a slide-block mounted in said frame and connected to said rod, a driving shaft, a gear on said shaft, a driven shaft, a driven gear carried thereby of one-half the size of and meshing with said driving gear, a carrier for said driven shaft journaled for oscillatory movement about the axis of said driving shaft, a crank on said driven shaft, a pitman connection between said crank and slide-block, an eccentric on said driving shaft, and a lever connection between said eccentric and carrier.

5. A needle-bar, a yoke at the lower end of said needle-bar, a cross-pin carried by said yoke, a needle-clamp-block slidably mounted on said cross-pin, a rotary bushing in which said needle-bar is journaled, spaced arms extending downwardly from said bushing, a cross-pin carried by said arms, one of said arms having a guideway for said yoke, a guide-block slidably mounted on said last-mentioned cross-pin and formed with a vertical guideway for said needle-clamp-block, and means carried by said bushing for reciprocating said guide-block on its supporting cross-pin.

crank and connected to impart circular movement to said loop-taker.

4. In a buttonhole sewing machine, a frame, a turret journaled in said frame, an oscillatory shuttle and bobbin mounted in said turret, an endwise reciprocating shuttle-actuating rod mounted in and coaxially with said turret, a slide-block mounted in said frame and connected to said rod, a driving shaft, a gear on said shaft, a driven shaft, a driven gear carried thereby of one-half the size of and meshing with said driving gear, a carrier for said driven shaft journaled for oscillatory movement about the axis of said driving shaft, a crank on said driven shaft, a pitman connection between said crank and slide-block, an eccentric on said driving shaft, and a lever connection between said eccentric and carrier.

5. A needle-bar, a yoke at the lower end of said needle-bar, a cross-pin carried by said yoke, a needle-clamp-block slidably mounted on said cross-pin, a rotary bushing in which said needle-bar is journaled, spaced arms extending downwardly from said bushing, a cross-pin carried by said arms, one of said arms having a guideway for said yoke, a guide-block slidably mounted on said last-mentioned cross-pin and formed with a vertical guideway for said needle-clamp-block, and means carried by said bushing for reciprocating said guide-block on its supporting cross-pin.
